RADIATOR

Jacob Ludvig Hellen, Kløfta, Norway

Application May 4, 1933, Serial No. 669,441
In Norway May 7, 1932

9 Claims. (Cl. 257—139)

The invention relates to radiators of the kind comprising two plates connected preferably by means of welding along their edges, one plate being provided with hollow ribs for the heating medium.

Known radiators of this kind have the disadvantage that the hollow ribs with a view to securing sufficient strength can be made with a comparatively small height only, as at the working pressure commonly used they easily expand with the result that both plates bend which may give rise to leakage. Such radiators therefore could be given only a comparatively small heating surface relatively to their dimensions (height and breadth).

According to the present invention this disadvantage is removed. The hollow ribs are curved in the longitudinal (vertical) direction in the form of a waving line or similar curved or broken line, instead of being made straight as usual. Tests as well as experience in use have proved that the height of such ribs may be increased to more than double the height allowable for straight ribs. A further advantage in connection with the said curving of the ribs is that their heat emission by convection is materially increased.

The necessary communication between the ribs for the circulation of the heat medium—as a rule steam or hot water—through the radiator may be secured by providing the plate, connected with the plate with the said ribs, with channels, preferably depressed in the plate, which are open towards said ribs. The said channels may be arranged in a suitable number transversally to the ribs in the other plate (i. e. horizontally), or one or more horizontal channels may be arranged at the upper and lower ends of the radiator and connected by means of vertical channels.

The plate (hereinafter termed front plate) connected with the rib plate (hereinafter termed back plate) also may be quite plane, which often is desirable from an architectonic point of view and which also gives a cheaper construction of the radiator. According to the invention the communication between the ribs in this case may be obtained thereby, that the parts between the ribs, in a plane normal to the front plate, are bent in a wavy line or broken line in such way that the said parts only in some places extend to the front plate and may be welded to the same, whereas in other places there is a free opening between adjacent ribs.

The number and location of the free openings between the ribs may vary. With a view to ob-

taining cheap manufacture, all ribs and all parts between adjacent ribs preferably are given the same shape, so that the said free openings between the ribs are located on a straight line across the radiator.

According to another embodiment of the invention, the communication between the ribs is secured by inserting flat iron pieces or pieces of other profiles between the two plates which pieces are welded to the front plate for stiffening the same, and preferably also to the parts between the ribs of the back plate, free passages between the ribs being left between the said flat iron or the like pieces. The front plate in this case is preferably made plane and with a bent flange along the edges, with a height corresponding to the height of the said pieces.

Further features of the invention are described hereinafter reference being had to the drawings which illustrate embodiments of the invention. Like reference numbers indicate corresponding parts in all figures.

Fig. 1 is a rear elevational view of a radiator showing the curved ribs, Fig. 2 is a vertical section through the radiator between two ribs, Fig. 25 3 is a horizontal section taken on the line a—a of Fig. 1. Fig. 4 is a front elevational view opposite to that shown in Fig. 1.

Fig. 5 is a rear elevational view of a modified design, Fig. 6 is a vertical section through the same. Figs. 7 and 8 are horizontal sections taken on lines b—b and c—c respectively of Fig. 5. Fig. 9 shows in a partial vertical section a modification of the radiator.

Fig. 10 is a rear elevational view of a further modified construction, Fig. 11 is a vertical section through the same and Fig. 12 a horizontal section taken on the line d—d of Fig. 10.

In the drawings 1 indicates the rear plate of the radiator with hollow ribs 2 which according to the invention are curved in the longitudinal or vertical direction in a wavy line. The ribs are closed at their top and bottom ends, preferably by welding. 3 indicates the plate—in this specification referred to as the front plate—connected to the rib plate 1 along the edges of both plates.

In the embodiment illustrated in Figs. 1—4, the front plate 3 is provided with depressions 4, 5, forming horizontal and vertical channels communicating with the hollow ribs so as to secure circulation of the heating medium through the radiator. In order to accommodate the inlet and outlet sockets 6 and 7 for the heating medium, the two outermost ribs 2a and 2b do not extend 55

to the top and bottom of the radiator, and the plate 1 in this place is flat so as to cover the channel 4. The path of the heating medium through the radiator is indicated with dotted lines in Fig. 4.

In the embodiment illustrated in Figs. 5-8, the communication between adjacent ribs 2 is obtained by bending the material between the ribs in certain places in the direction away from the front plate 3, so that passages as indicated at 9, 9 are formed between the ribs. The front plate 3 is plane with a bent flange 10 along the edges, where it is welded to the edges of the rib plate 1. The parts between the ribs are in the places where they are not bent, in contact with the front plate and may be welded to this plate at as many places as considered necessary for the stiffening of the same. The amount that the outer wall of the outermost ribs on both sides of the radiator projects forwardly is decreased corresponding to the extent of the flange of the front plate and welded to the same as indicated at 11, in Fig. 7.

In the modification shown in Fig. 9, the front plate 3 is wholly plane, the bent parts of the plate 1 between the ribs being located at some distance from the ends of the ribs. In other respects the construction is the same as shown in Figs. 5-8, of course with the exception that the horizontal dimension of the outer walls of the outermost ribs on both sides of the radiator is the same as the amount of projection of the ribs.

Figs. 10-12 illustrate an embodiment of the radiator in which the communication between the ribs is obtained by fitting of flat iron pieces 12, 12 between the plates. These pieces are welded to the front plate 3 at as many places as necessary for stiffening of the plate, and preferably also welded to the parts of the back plate between the ribs. The front plate is provided with a bent flange around its edges, projecting an amount corresponding to the width of the flat iron pieces, and welded to the rib plate.

In the embodiment shown the flat iron pieces are parallel and the same distance one from the other, and perpendicular to the ribs, but they may be arranged at different distances and at other angles to the ribs as may be found suitable for the stiffening of the front plate and the communication between the ribs.

In the radiators illustrated in the Figs. 5-9 and Figs. 10-12, the outer rib 2c on the left-hand side of the drawings is made somewhat broader than the other ribs in order to obtain a cross section sufficiently large to enable the inlet and outlet sockets 6 and 7 for the heat medium to be located on the side of the rib.

Preferably, flat iron pieces 13 are arranged transversely on the top of the ribs in the upper and lower part of the radiator as shown in Figs. 5-8, welded to some or all of the ribs and serving

partly for stiffening the ribs and partly for supporting the radiator.

What I claim is:

1. A radiator comprising two plates connected along their edges, one of the plates being provided with hollow ribs for the heating medium, the parts of this plate between the ribs being bent in some places in the direction away from the other plate so as to form passages between adjacent ribs. 5

2. A radiator according to claim 1, characterized in that the plate connected to the plate provided with hollow ribs is entirely plane.

3. A radiator according to claim 1, characterized in that the plate connected to the plate provided with hollow ribs is plane and along its edges provided with a flange the height of which corresponds to the depth of the said incavation of the parts between the ribs. 15

4. A radiator comprising two plates connected along their edges, one of the plates being provided with hollow ribs for the heating medium, iron bars being fitted at suitable places between the plates and welded to both plates so as to secure communication between adjacent ribs. 20

5. A radiator according to claim 4, characterized in that the plate connected to the plate provided with hollow ribs is plane and along its edges provided with a bent flange the height of which corresponds to the height of the bars inserted between the plates. 30

6. A radiator comprising two plates connected along their edges, at least one of the plates being provided with hollow ribs for a heating medium one of the ribs being made with a cross section larger than the cross section of the other ribs and sufficiently large to enable inlet and outlet sockets for the heating medium to be located at the side of this rib.

7. A radiator comprising two plates connected along their edges, at least one of the plates being provided with hollow ribs for a heating medium, iron bars being welded to the tops of the ribs transversally to the same in the upper and lower part of the radiator for stiffening of the ribs and for supporting of the radiator. 45

8. A radiator of the character described including, in combination, two plates welded together at their outer edges, one plate only having projecting hollow ribs curved in a vertical direction and one plate having channels affording communication between adjacent ribs. 50

9. A radiator of the character described including, in combination, two sheet metal plates welded together at their outer edges, one plate only having projecting hollow ribs curved in a vertical direction closed at their ends and extending substantially throughout the height of the radiator and one plate having channels affording communication between adjacent ribs. 60

JACOB LUDVIG HELLEN.
